SHUTTLECOCK CONTAINER

William Charles Carlton, Fitches, Finchingfield,
Essex, England

Filed Aug. 26, 1965, Ser. No. 86,723

Claims priority, application Great Britain May 22, 1965

Term of patent 14 years

(Cl. D58—17)

FIG. 1 is a front elevation of a shuttlecock container embodying my new design.

FIG. 2 is a top plan view of the same.

FIG. 3 is a bottom plan view of the same.

FIG. 4 is an enlarged fragmentary view taken on the line 4—4 of FIG. 1.

FIG. 5 is an enlarged fragmentary view taken on the line 5—5 of FIG. 1, showing the removable closure or cap of the container frictionally held in the bottom end of the container.

I claim:

The ornamental design for a shuttlecock container, substantially as shown and described.
